UNITED STATES PATENT OFFICE

150,663

DESIGN FOR A CLOCK FRAME OR SIMILAR ARTICLE

Kenneth A. Van Dyck, Rochester, N. Y., assignor
to Eastman Kodak Company, Rochester, N. Y.,
a corporation of New Jersey

Application December 4, 1947, Serial No. 142,953

Term of patent 14 years

(Cl. D42—7)

To all whom it may concern:

Be it known that I, Kenneth A. Van Dyck, a citizen of the United States, residing at Rochester, in the county of Monroe and State of New York, have invented a new, original, and ornamental Design for a Clock Frame or Similar Article, of which the following is a specification, reference being had to the accompanying drawings, forming a part thereof, in which:

Fig. 1 is a front elevational view of a clock frame or similar article showing my new design;

Fig. 2 is an end elevational view thereof;

Fig. 3 is a perspective view taken from the front thereof; and

Fig. 4 is a fragmentary bottom plan view of the same, the broken line showings seen in Figs.

1 and 2 have been omitted from Figs. 3 and 4 for convenience of illustration.

I claim:

The ornamental design for a clock frame or similar article, as shown and described.

KENNETH A. VAN DYCK.
